LEWIS W. SPENCER, OF NEW YORK, N. Y., ASSIGNOR TO "SCHREIBER CORNET MANUFACTURING COMPANY," OF THE SAME PLACE.

Letters Patent No. 63,761, dated April 9, 1867.

IMPROVEMENT IN MACHINES FOR FORMING THE BELLS OF CORNETS.

The Schedule referred to in these Letters Patent and making part of the same.

TO ALL WHOM IT MAY CONCERN:

Be it known that I, LEWIS W. SPENCER, of the city, county, and State of New York, have invented a new and useful Machine for Forming the Bell of Cornets, and other like metallic musical instruments; and I do hereby declare that the following is a full, clear, and exact description thereof, reference being had to the accompanying drawings, making part of this specification, in which—

Figure 1 is a front elevation of the machine; and

Figure 2 a vertical section thereof.

The operation of forming the bell of such instruments has heretofore been attended with serious difficulties and much labor; but by means of my said invention I am enabled to accomplish the required result in the most perfect manner and with very little labor.

As in the usual process generally practised, the sheet metal required to form such a bell is bent in the form of a frustum of a cone, as represented by Figure 3, and the edges brazing. The small end of this hollow frustum is inserted in the central hole of the disk of lead *a*, and this disk placed on the upper edge of a hollow die *b*, which I prefer to make of steel with the inside of the form of the bell which is to be made, but shorter, as represented. This die is secured to a plate, *c*, which is connected with the upper surface of a bench, *d*, by a fulcrum-pin, *e*, for a purpose to be presently described. A former, *f*, of the form of the bell to be formed; and which I prefer to make of steel, is secured to the under side of a cross-head, *g*, with the larger end next to the said cross-head. This former is secured to the cross-head by a pintle, *h*, projecting from its upper end, and which is fitted to a hole of corresponding size in the cross-head, and a pin is then driven into a hole in the cross head and in the pintle. The cross-head *g* is adapted to slide on two vertical and parallel rods *i i*, firmly connected with the bench *d*, and connected together at top by a cross-bar, *j*, in which is journalled a strong nut, *k* so that it can turn therein without moving up or down, and to this nut is fitted a strong screw-shaft, *l*, which is firmly secured by its lower end to the cross-head *g*. After the blank has been inserted in the die *b*, as before stated, and brought in line under the former *f*, the nut *k* is turned by any suitable power, but with a regular motion, to force down the follower into the blank; and by this downward motion of the former the blank is forced down into the disk of lead *a*, which, resting on the upper edge of the die, is gradually forced down into the cavity of the die and spread and its bore enlarged; but during these changes of form the lead presents such a resistance to the sheet-metal blank that the inner surface thereof is forced into close contact with the former and by degrees, and, as the former descends, made to assume the exact form of the former, both outside and inside. When the former has been forced down to the full extent, the motion of the nut is reversed, the former drawn out, and the plate which holds the die turned out from under the former, and the formed bell taken out. The machine is then ready to receive another blank.

A good bell can be thus formed at one operation, but a more perfect result can be produced by two or three operations, and to do this I have two or three formers, the last being of the exact form intended to be ultimately given to the bell, and the others being only of an approximate form. If I use three formers in succession, I subject the blank to the operation of the machine with a former which is nearest in form to the form of the blank, and then to a like operation with the second former, which should be a mean between the first and the last, and finally, with the last former, which completes the bell. In this way the metal is subjected to less strain than when completed at one operation. The lead disk will best subserve the purpose above described if it be made thicker immediately around the central hole, and when so made I use it with the said projection upwards when I make the bell at one operation, and downward when I form the bell by two or more operations.

What I claim as my invention, and desire to secure by Letters Patent, is—

The combination of the die, the leaden (or equivalent) disk, the former, and the follower, substantially as and for the purpose described.

L. W. SPENCER.
